Application February 14, 1955, Serial No. 34,504

Term of patent 14 years

(Cl. D26—14)

To all whom it may concern:

Be it known that I, Isaac Heller, a citizen of the United States of America and a resident of Maplewood, county of Essex, and State of New Jersey, have invented a new, original, and ornamental Design for a Combined Telephone Hand Set and Stand, of which the following is a specification, reference being had to the accompanying drawing forming a part thereof.

Figure 1 is a front perspective view from one end of a combined telephone hand set and stand embodying the new design and showing the telephone hand set removed from the stand;

Figure 2 is a rear perspective view from the other end thereof showing the telephone hand set on the stand; and

Figure 3 is a rear perspective view of the stand, with the telephone hand set omitted.

I claim:

The ornamental design for a combined telephone hand set and stand, as shown.
